UNITED STATES PATENT OFFICE.

CHARLES A. HAUSWIRTH, OF EAST ORANGE, NEW JERSEY.

VALVE-LIFTING DEVICE.

1,116,699.

Specification of Letters Patent. Patented Nov. 10, 1914.

Application filed December 11, 1913. Serial No. 805,924.

To all whom it may concern:

Be it known that I, CHARLES A. HAUSWIRTH, citizen of the United States, residing at East Orange, in the county of Essex and 5 State of New Jersey, have invented certain new and useful Improvements in Valve-Lifting Devices, of which the following is a specification.

The present invention relates to a valve 10 spring compressor which is designed for use when dismounting the puppet valves of internal combustion engines such as are commonly employed upon automobiles, the object of the invention being to provide a 15 device of this character which embodies novel features of construction whereby it may be either hooked into the opening at the top of the valve casing of the engine or fitted upon the cam rod, according to which 20 position of the tool may be most convenient.

Further objects of the invention are to provide a valve spring compressor which is comparatively simple and inexpensive in its construction, which can be quickly placed 25 in position or removed therefrom, which will enable the valve spring to be readily compressed preparatory to unseating and removing the valve, and which is peculiarly constructed so that it can be collapsed and 30 will occupy but a small amount of space when not in use.

With these and other objects in view, the invention consists in certain novel combinations and arrangements of the parts as will 35 more fully appear as the description proceeds, the novel features thereof being pointed out in the appended claims.

For a full understanding of the invention, reference is to be had to the following description and accompanying drawing, in 40 which:—

Figure 1 is a side elevation of an engine cylinder, showing one manner of applying the valve spring compressor thereto. Fig. 45 2 is a similar view showing another manner of applying the valve spring compressor to the engine. Fig. 3 is an enlarged plan view of the operating lever, showing the same as distended and in position for use. 50 Fig. 4 is a similar view showing the operating lever in a folded position. Fig. 5 is an enlarged perspective view of the fulcrum bar. Fig. 6 is a longitudinal sectional view 55 through the operating lever, on the line 6—6 of Fig. 3, showing the fulcrum bar in engagement therewith and also showing the

valve rod and valve spring, portions being broken away. Fig. 7 is an enlarged transverse sectional view through the spring engaging yoke, the said view being taken on 60 the line 7—7 of Fig. 3.

Corresponding and like parts are referred to in the following description and indicated in all the views of the drawing by the same reference characters.

Referring to Fig. 1, the numeral 1 designates a diagrammatic representation of a conventional form of internal combustion engine, the cylinder being provided at the top thereof with the usual laterally projecting valve casing 2, which has an opening 3 in the upper end thereof, the said opening being normally closed by a suitable plug, although this plug is removed preparatory to applying the valve lifting and spring compressing tool to the engine. In Fig. 2 the character 1^a also designates a diagrammatic representation of an internal combustion engine which has a valve casing 2^a at the top thereof. Each form of engine has the usual 70 puppet valve, the said puppet valves being provided with the valve stems 4 which project downwardly from the valve casings and are surrounded by the valve springs 5 which are held under compression by suitable nuts 75 or keys 6 at the lower ends of the valve stems. In Fig. 2 a cam actuated rod 7 which is slidably mounted within the usual 80 guide boss 8 projects upwardly from the base of the engine and is arranged in alignment with the valve stem 4 so as to periodically lift the same and unseat the valve in 85 the operation of the engine.

The operating lever 9 of the spring compressing tool, shown more clearly by Figs. 95 3 and 4, comprises two sections 9^a and 9^b which are hinged or pivotally connected at 10. The section 9^a of the lever is formed of a pair of spaced strips adapted to receive the fulcrum bar 11 between the same, the 100 said strips being rigidly connected by suitable fastening members and having the spacing blocks 12 interposed between opposite end portions thereof. A fulcrum pin 13 connects the spaced strips at an intermediate point in their length, and the free ends of the said strips are diverged at 9^c to provide a bifurcated end within which a spring engaging yoke 14 is pivotally mounted. Opposite sides of the yoke 14 are provided 105 with the trunnions 15 which are journaled in the arms of the bifurcated end of the 110

operating lever 9 and are preferably offset from the plane of the yoke, as indicated more clearly by Fig. 7 so as to prevent the end of the valve spring coming into engagement with the lever when the tool is in use. Owing to the pivotal mounting of the spring engaging yoke 14 it will be obvious that it can swing about the trunnions 15 and accommodate itself to the valve spring regardless of the inclination or angle to which the main lever 9 may be tilted. The opposite section 9^b of the operating lever is formed from a single strip of material and comprises spaced sides and an outer enlarged and looped end 9^e. The spaced sides have a length corresponding to the spaced sides of the lever section 9^a, and are adapted to receive the lever section 9^a between the same, the arms 9^c of the bifurcation as well as the spring engaging yoke 14 fitting within the looped end 9^e. The two lever sections 9^a and 9^b are pivotally connected at 10 and may be either swung outwardly into alignment with each other, as indicated by Fig. 3, or the section 9^a folded rearwardly so as to be completely received within the section 9^b, as indicated by Fig. 4. When in this latter position the lever 9 occupies but a very small amount of space and can be readily packed in a tool case. The outward swinging movement of the lever section 9^a is limited by engagement with a stop bar 17 applied to the pivot end of the lever section 9^b. The ends of the stop bar are shown as extended laterally so as to embrace and fit against the exterior of the lever section 9^b, the said laterally extended ends being riveted or otherwise rigidly connected thereto, as indicated at 18. As previously stated the fulcrum bar 11 is adapted to fit loosely between the spaced sides of the lever section 9^a, and this fulcrum bar is provided at one edge thereof with a series of notches 19 which are inclined toward one end thereof. Each end of the fulcrum bar 11 is also provided with an opening 20, and one end of the fulcrum bar is designed to be connected by a flexible member such as the chain 21 to a hook 22. In the present instance the shank of the hook 22 is returned at 23 for engagement with one end of the chain 21, the opposite end of the chain being engaged by a yoke 24 which straddles one end of the fulcrum bar 11 and has the arms thereof connected by a pin 25 passing through the opening 20 of the fulcrum bar. Suitable means such as the cotter pin 26 may be provided for holding the pin 25 removably in position.

One manner of using the tool is illustrated by Fig. 1, in which the hook 22 is placed in engagement with the opening 3 at the upper end of the valve casing 2, the fulcrum bar 11 inserted between the spaced sides of the lever section 9^a and a suitable

one of the notches 19 brought into engagement with the pin 13. The spring engaging hook 14 is properly positioned under the valve spring 5 and a downward pressure applied to the looped outer end 9^e of the operating lever 9. This results in compressing the valve spring 5 and lifting the valve so that the key or nut 6 can be readily removed. Another manner of using the tool is illustrated by Fig. 2, in which the chain 21 is detached from the fulcrum bar and hook member and the returned end 23 of the shank of the hook brought into engagement with the opening 20 at the opposite end of the fulcrum bar 11. The hook 22 may now be placed in engagement with the cam actuated rod 7 or the guide boss for the same, according to the relative size of the hook and engine parts. The fulcrum bar 11 is then swung upwardly from the end of the hook 22 and the operating lever 9 applied thereto substantially as in the previous instance. It will be observed, however, that when the tool is used as shown by Fig. 1, the chain 21 is in engagement with the upper end of the fulcrum bar 11, both the chain and fulcrum bar acting under tension, while when the tool is used as indicated by Fig. 2, the lower end of the fulcrum bar 11 is supported by the hook 22 and the fulcrum bar acts under compression. The tool may be used in either way, according to which is found most convenient, and when not in use the operating lever 9 can be folded together and the entire tool packed in a very small amount of space.

Having thus described the invention, what I claim as new and desire to secure by Letters Patent, is:—

1. An automobile valve lifter including an operating lever, spring engaging means at one end of the operating lever, a fulcrum bar for the lever, an engine engaging member, and means for operatively connecting the engine engaging member to either end of the fulcrum bar.
2. An automobile valve lifter including an operating lever, spring engaging means at one end of the operating lever, a fulcrum bar for the operating lever, a hook member adapted to engage either an opening in the valve casing or a cam actuated rod, and means for operatively connecting the hook member to either end of the fulcrum bar.
3. An automobile valve lifter including a fulcrum bar having an opening in one end thereof, a hook having the shank thereof returned for engagement with the said opening of the fulcrum bar, a flexible member for connecting the hook to the opposite end of the fulcrum bar, an operating lever provided with means for engagement with the fulcrum bar, and spring engaging means upon the operating lever.
4. An automobile valve lifter including a

fulcrum bar having an opening in each end thereof and provided at one side with a series of inclined notches, an engine engaging hook having the shank thereof returned and adapted to engage one of the openings of the fulcrum bar, a flexible member connected to the hook, means for detachably connecting the flexible member to the opening in the opposite end of the fulcrum bar, an operating lever provided with a fulcrum pin adapted to engage one of the inclined notches of the fulcrum bar, and spring engaging means upon the operating lever.

5. An automobile valve lifter including an engine engaging member, a fulcrum bar supported thereby, a collapsible operating

lever formed in hinged sections, one of the sections being an open frame adapted to receive the other section and the free end of the inner section terminating in an enlarged 20 bifurcated end, while the free end of the outer section terminates in an enlarged loop to receive the said bifurcation when the lever is folded, and spring engaging means mounted within the said bifurcation. 25

In testimony whereof I affix my signature in presence of two witnesses.

CHARLES A. HAUSWIRTH.
